[57] CLAIM

The ornamental design for a patient headwall unit, as shown and described.

DESCRIPTION

FIG. 1 is a perspective view of the patient headwall unit of the design;

FIG. 2 is a front elevation thereof on a reduced scale;

FIG. 3 is a side elevation thereof on a reduced scale;

FIG. 4 is a top plan view thereof on a reduced scale illustrating the cross-sectional configuration at the upper section of the unit, the top being otherwise plain and unornamented; and

FIG. 5 is a bottom plan view thereof on a reduced scale illustrating the cross-sectional configuration at the bottom of the unit, the bottom being otherwise plain and unornamented.

The side opposite from that shown in FIG. 3 is a mirror image of FIG. 3. The back is plain and unornamented.

FIG. 1
